US0D1013252S

(12) **United States Design Patent** (10) Patent No.: **US D1,013,252 S**
(45) Date of Patent: ** Jan. 30, 2024

(54) **ELECTRONIC VAPORIZER**

(71) Applicant: **Shenzhen Itsuwa Technology Company Limited**, Shenzhen (CN)

(72) Inventor: **Ruyun Guo**, Shenzhen (CN)

(73) Assignee: **Shenzhen Itsuwa Tech Co. Ltd.**

(**) Term: **15 Years**

(21) Appl. No.: **29/791,315**

(22) Filed: **Jan. 7, 2022**

(30) **Foreign Application Priority Data**

Sep. 23, 2021 (CN) 202130630951.8

(51) LOC (14) Cl. **27-07**

(52) U.S. Cl.

USPC **D27/162**

(58) **Field of Classification Search**

USPC D27/100, 101, 162, 163–165, 167, 169, D27/172, 183, 185–192, 194; D23/360, D23/366; D24/110, 110.5

CPC A24F 40/00; A24F 40/10; A24F 40/20; A24F 40/40; A24F 40/42; A24F 40/44; A61M 15/00; A61M 15/06

See application file for complete search history.

(57) **CLAIM**

The ornamental design for an electronic vaporizer, as shown and described.

DESCRIPTION

FIG. 1 is a perspective top view.

FIG. 2 is a perspective bottom view.

FIG. 3 is a front view.

FIG. 4 is a back view.

FIG. 5 is a right side view.

FIG. 6 is a left side view.

FIG. 7 is a top view; and,

FIG. 8 is a bottom view.

The diagonal line shading represents transparency of the outer cover over an opaque inner portion. Said shading does not represent surface ornamentation. The broken line portion of the drawing forms no part of the claim.

1 Claim, 5 Drawing Sheets
